MARTIN FOX, OF CHICAGO, ILLINOIS, ASSIGNOR TO THE SENG COMPANY, OF CHICAGO, ILLINOIS, A CORPORATION OF ILLINOIS.

CORNER LOCK.

Application filed April 9, 1923. Serial No. 630,756.

This invention relates to a side rail corner lock for beds and is applicable either to wood or metal bed ends. Among the objects of the invention are: to provide a simple attachment housing which can be made of a minimum amount of material and with few bending operations; to strengthen the housing itself by the application of the side rail; to utilize only the side rail in attaching it to the housing; to additionally strengthen the housing by the attachment of the cross rail; and in general, to produce the construction herein shown and described.

In the accompanying drawing, Fig. 1 is a side elevation showing a corner lock embodying this invention; Fig. 2 is a front view showing the side rail in section; Fig. 3 is a plan view; Fig. 4 is a section taken on the line 4-4 of Fig. 3; Fig. 5 is a perspective of the housing; Fig. 6 shows a blank from which the housing is made; and Fig. 7 is a section of this supporting stud.

In carrying out this invention a housing 1 is formed up out of a single blank 2 of material, as shown by Fig. 6. The blank and the housing comprises a central portion 3 with perforations 4 through which fastening bolts 5 are inserted for securing the housing to a post 6. If the post is round, as shown in the drawings, this portion 3 is rounded to conform to the post, but if applied to a square post, the surface is made flat. At the sides of the central portion are fold lines 7 and 8 which make the sides 9 and 10 respectively. Extending from the side 9 is an ear 11 which is folded upwardly on the inside of the box or housing, and extending from the other side 10 are ears 12 and 13 the first of which is bent downwardly or within the box and the other one, 13, is bent outwardly. All of these ears are formed with perforations 14, and when the sides are folded together the ears 11 and 13 will be disposed at right angles to each other for the attachment of a cross rail 15 by means of which the housings are properly spaced apart but secured together in pairs, the cross bars being attached by means of rivets 16 inserted therethrough and through the perforations of the ears 11 and 13.

The ear 12 at the top of the housing is preferably bent inwardly at a slight distance below the upper edge of the opposite side 9, as clearly shown in Fig. 2, and secured in the perforation of this ear is a short stud 17, the

upper end of which is slightly bevelled and extends above the upper face of the ear.

In the outer side 9 is a perforation 18 for receiving a shouldered stud or rivet 19 with its head 20 on the inside of the housing, the inner face 21 of the head being slightly bevelled to the shouldered portion 22. A side rail 23 which is adapted to engage the studs 19 and 17 is angular in form with a slot 24 in the vertical web which fits over the shouldered portion 22 of the stud 19 and with a perforation 25 in the horizontal web which engages over the bevelled end of the stud 17 in the ear 12. The inclined face of the stud 19 permits the lower edge of the vertical web of the side rail 23 to engage between the head 20, the side 9, and the slot 24 to engage over the stud. In practice this slot 24 is very slightly bevelled or widened at its outer end so that the stud 19 will be seated at the bottom of the slot. The extremity of the rail is straight or square along the vertical web at this end 26, and the housing is formed with a corresponding flattened surface 27 which this end abuts. The horizontal web is cut off upon a line 28 so that this portion of the side rail will clear the curved central portion 3 of the housing blank, as shown more clearly in Fig. 3.

The extremities of the connecting cross bar 15 are preferably cut off at 29, as clearly shown in Fig. 2 in order that the vertical web of the side rail will be seated in the housing clear of any engagement therewith.

With this construction it is obvious that the parallel sides of the housing are separately held together both at top and bottom when the side rails are in position; the cross bar 15 connecting the lower portions of the sides by means of the ears 11 and 13 to which it is riveted, and the angle bar or side rail engaging the studs 19 and 17 over the top of the sides. It will also be seen that with the side rail in position a neat appearing housing will be formed, as the top of the side rail is flush with the upper edge of the side 9 (see Fig. 2) with only a portion of the stud 17 projecting above the horizontal web of the side rail. As the studs 17 and 19 are quite a distance apart, the side rail makes a rigid connection in the housing, and as the studs are drawn up tightly by the application of the side rail, there is very little play or tendency to become loosened. Furthermore, the extremity 26 of the vertical web

bears firmly against the plane surface 27 provided for that purpose in the housing and holds the rail firmly in the proper relation with respect to the stud 19. As the housing 5 blank and the rail are all accurately cut and formed with dies, the rails are interchangeable end for end with any others and may be fitted into any of the boxes or housings.

To disengage the rail from the housing it 10 is necessary only to raise it from its engagement with the studs 17 and 19. It may be necessary at times to tap the underside of the rail sharply with a hammer as the rail is intended to make a tight fit but not a wedging 15 fit. A circular boss 30 may be provided in the outer side 9 surrounding the riveted end of the stud 19 for ornamental purposes and to allow a slight give to the stud.

I claim:

20 1. In a corner lock, a sheet metal housing having one side with an inside projection and its upper edge at a height slightly above and spaced from the other side, and an angle bar side rail having a notch in one edge for engagement with the projection at the side of the housing and with the other web of the angle bar flush with the upper edge of the said higher side and also engaging the said other side of the housing for binding the spaced sides together.

25 2. In a corner lock, a hollow housing having two sides spaced apart, and one formed with an inwardly turned ear at the top, a projection extending upwardly from the ear, 30 and an angle bar engageable with the projection and also having means engaging the other side of the housing, thus binding the two sides of the housing together.

35 3. In a corner lock, a housing formed with opposite sides, one of which has an inner projection, means for connecting the sides across the bottom, an angle bar, one web of which has a slot engageable with the projection, and an ear projecting inwardly from 40 the top of the other side for engaging the other web of the angle bar, the angle bar thus binding the housing sides together across the top.

45 4. In a corner lock, a hollow housing having parallel spaced sides, one formed with an inwardly turned ear at the top below the level of the other side, means projecting inwardly from the said other side and means projecting upwardly from said ear, and an 50 angular side rail engageable with both of said means and binding the sides together.

55 5. In a corner lock, a hollow housing having an open top with sides having projections at right angles to each other, and an angle bar side rail insertable therein with 60 openings to engage the said projections and one web of the angle bar closing the top of the housing.

65 6. In a corner lock, a housing having spaced sides and an open top with an ear

projecting inwardly from one of them, projections from the upper face of the ear and from the inner face of the opposite side, and an angle bar side rail insertable in the housing having a slot in one web to engage the 70 inside projection, and with a perforation in the other web to engage the projection on the ear, the latter web forming a top for the housing and binding the sides together.

7. In a corner lock, a single blank forming 75 a housing with spaced sides, the lower edges of which are provided with ears turned in the same direction but at right angles to each other, a cross rail connecting the said ears for strengthening the lower portion of the 80 housing, projections from the opposite sides, and an angle bar side rail having openings to engage the projections for binding the upper portion of the sides together and for closing the top of the housing.

8. In a corner lock, a housing for attachment to a post comprising a pair of sides, one formed with an ear turned inwardly at the top, a supporting member extending inwardly from the other side, said supporting member having a head with a bevelled inner face, another projection on the said ear, and an angular side rail with openings fitting over said member and engaging said projection thereby binding the opposite sides together.

9. In a corner lock, a housing formed of sheet material with spaced sides and a straight abutment surface in the angle formed in bending one of the sides, a headed projection extending inwardly from this side, an ear turned inwardly from the top of the other side having an upward projection, and an angle bar side rail having a slot to fit over the headed projection, a perforation to 105 fit over the projection in the ear, and a contact surface at the end to engage the straight abutment surface in the housing.

10. In a corner lock, a housing for attachment to a post comprising spaced sides, a supporting projection extending inwardly from one of the sides, an inwardly turned ear at the top of the other side, and a projection extending from the upper face of the ear with a bevelled extremity, and an angular side rail 110 insertable in the housing with a slot to fit over the supporting projection, and an opening at right angles thereto to fit over the bevelled projection of the ear.

11. In a corner lock, a housing with spaced 115 sides, an angle bar side rail, means for mounting the side rail against the inner face of one of the housing sides and across the top between them, and a cross bar connected to the lower edges of the housing sides, the extremity of the cross bar being cut off at an angle to admit one web of the angle bar between the end of the cross bar and the adjacent inner face of the housing.

12. In a corner lock, a single piece hous-

ing formed with three ears, the sides of the housing being spaced apart, and one of the ears being bent inwardly toward the opposite side at a distance below the upper edge 5 of the opposite side, the other two ears being bent in the same direction at right angles from the opposite sides adjacent the bottom thereof, means for connecting the last two ears and strengthening the housing at the bottom of the sides, an angular side rail and 10 means for mounting the angular side rail against the inner face of one of the housing sides and upon the ear of the other side so that the outer top face of the side rail is flush with the upper edge of the other housing side.

MARTIN FOX.
